C. W. KNIGHT

AUTOMATIC STORM SASH OPERATOR

Filed Oct. 19, 1922

Patented Feb. 3, 1925.

1,524,716

UNITED STATES PATENT OFFICE.

CHARLES W. KNIGHT, OF MINNEAPOLIS, MINNESOTA, ASSIGNOR TO RALPH T. KNIGHT,
OF MINNEAPOLIS, MINNESOTA.

AUTOMATIC STORM-SASH OPERATOR.

Application filed October 19, 1922. Serial No. 595,568.

To all whom it may concern:

Be it known that I, CHARLES W. KNIGHT, a citizen of the United States, residing at Minneapolis, in the county of Hennepin and 5 State of Minnesota, have invented certain new and useful Improvements in Automatic Storm-Sash Operators; and I do hereby declare the following to be a full, clear, and exact description of the invention, such as 10 will enable others skilled in the art to which it appertains to make and use the same.

My invention relates to automatic storm sash operators of the type which connects an inside sliding window sash to a swinging 15 storm sash, whereby the opening and closing movements of the window sash will impart like movements to the storm sash, thus avoiding the effort and inconvenience of opening and closing the storm sash independently of 20 the opening and closing of the window sash.

The primary object of my invention is to provide an operator that will exert a constant push on the storm sash directly from the window casing, through its entire opening movement, and exert a constant pull on the storm sash that is directly toward the window frame throughout its entire closing movement. This direct push on the storm sash is highly important during the the initial opening movement of the storm sash to start the same from its seat in the window casing, and the direct pull on the storm sash during the final closing movement thereof is also highly important to draw the storm 30 sash onto its seat.

A further object of the invention is to provide a storm sash operator that will firmly hold such a sash in position whether closed, open, or in an intermediate position, 40 and which operator may be quickly and easily attached to or detached from the inside sliding window sash.

A still further object of the invention is to insure that the storm sash may never be 45 neglectfully left open when the inside sliding window sash is closed.

A still further object of the invention is to provide an extremely simple storm sash operator of comparatively small cost to manufacture, and, at the same time, very positive in its action.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary view of a window 60 frame in which is mounted an inside sliding window sash and a swinging storm sash, to which sashes the invention is applied;

Fig. 2 is a view corresponding to Fig. 1 with the exception that the two sashes are 65 open; and

Fig. 3 is a fragmentary detail view with some parts sectioned on the line 3—3 of Fig. 1, on an enlarged scale.

The numeral 4 indicates a window frame, 70 as an entirety, with the exception of its water table 5 and the parting strip 6 between the upper and lower vertical sliding window sashes, only the latter of which is shown, and indicated by the numeral 7. 75 This window frame 4 has an outside casing 8 which affords a stop against which a storm sash 9 is seated, when closed, and which storm sash is attached at its upper end to said casing by the customary separable 80 hinges, not shown, for outward swinging movement. The lower horizontal edges of the two sashes 7 and 9 are beveled to snugly fit against the water table 5 when said sashes are closed. The parts thus far described are 85 all of standard construction and have been illustrated simply for the purpose of showing the invention applied in working position.

Referring now in detail to the improved 90 automatic storm sash operator, the numeral 10 indicates a strong flat bar of spring metal, having in one of its ends an elongated eye 11 through which is inserted a staple 12 driven into one of the stiles of the storm 95 sash 9 to pivotally connect said bar thereto. A wearing plate 13 is interposed between the storm sash 9 and bar 10 to prevent said bar from cutting into the storm sash, and which wearing plate is held in position by forming therein holes through which the legs of the staple are inserted before driving the same into the storm sash and by one or two screws.

In the other end of the bar 10 is an eye 14 105 arranged to receive an inverted hook, 15, screwed into the window sash 7 directly below the staple 12, to detachably connect said bar 10 to the window sash. A wearing plate 16, through which the hook 15 extends, 110

is secured to the window sash 7 by wood screws 17. To prevent the bar 10 from becoming accidentally detached from the hook 15, there is mounted on the stem of said hook, between the bar 10 and the wearing plate 16, a swinging guard 18 which extends horizontally under the hook 15 and vertically outward of and above the free end thereof, as best shown in Fig. 1.

10 Attached to the window casing 8, just below the staple 12 when the storm sash 9 is closed, is a fulcrum 19 on which the bar 10 slides endwise during the opening and closing movements of the sashes 7 and 9. During the opening and closing movements of the window sash 7, the bar 10 bends in a curve over the fulcrum 19, and the section thereof between said fulcrum and the window sash 7, is in a vertically disposed position, and the section thereof between said fulcrum and the storm sash 9 is in a horizontally disposed position and thereby causes said bar to impart a direct push on the storm sash 9 away from the window frame, and a direct pull on the storm sash toward the window frame. When the window sash 7 is open, as shown in Fig. 2, the bar 10 is in a horizontal position above the fulcrum 19, and when said sash is closed, the bar 10 is bent over the fulcrum 19 in the form of a bow and thereby is placed under sufficient tension to hold the storm sash 9 closed and tightly seated in the window frame, as shown in Fig. 1. As previously stated, a direct push on the storm sash 9 away from the window frame 4 is highly important to force the window sash 7 from its seat; and likewise, a direct pull on the storm sash 9, toward the window frame, during its closing movement is highly important to draw the storm sash onto its seat.

It may be here stated that the tendency of the spring bar 10 is to straighten, and hence will, at all times, yieldingly bear upon the fulcrum 19 except when the windows are in an open position as shown in Fig. 1, and at which time the bar 10 is straight.

Formed with the attaching plate of the fulcrum 19 is a stop lug 20 for the bar 10 in case the same is lifted from said fulcrum. The plate with which the fulcrum 19 and stop lug 20 are formed affords a wearing surface for the bar 10 to prevent the same from cutting the window casing 8. In place of forming the bar 10 from a piece of flat metal, the same may be formed from a piece of relatively heavy spring wire. While only one of the automatic storm sash operators has been shown in the drawings, it is, of course, understood that there will be two employed, in actual usage, on each storm sash.

After the staple 12, wearing plate 13 and bar 10, held by said staple, are once secured to the storm sash 9 and the fulcrum 19 and stop lug 20 secured to the window casing 8,

and the wearing plate 16, hook 15 and guard 18 secured to the window sash 7, said parts are permanent and do not have to be changed. In applying the storm sash 9 to the window frame 4, it is only necessary, 70 after the same is properly hung, to open said sashes, substantially as indicated in Fig. 2, so that the bar 10 may be extended between the fulcrum 19 and stop lug 20 without bending, and then interlock its free end with the hook 15, after swinging the guard 18 into an inoperative position, as indicated by broken lines in Fig. 3. To detach the bar 10 from the hook 15, during the removal of the storm sash from the window frame, like operations are required except that the bar 10 is detached from the hook 15 after the guard 18 has been moved into an inoperative position. When the storm sash 9 is removed from the window frame 4, the bar 10 will lay flap against said storm sash thus permitting a plurality of storm sashes, equipped with my improved operator, to be stored, in close contact, the one with the other.

I do not wish to be confined to the precise manner of mounting the fastening devices illustrated herein or to the shape of the operating bar, as in various ways the details may be modified and still be within the scope of my invention.

The above described invention has, in actual usage, proven highly efficient for the purpose had in view.

What I claim is:

1. The combination with a window frame, 100 a sliding sash and a swinging sash mounted in the window frame, of means operated by the sliding sash during its opening movement to impart a constant direct push on the storm sash away from a fixed point on the window frame to open the storm sash.

2. The combination with a window frame, 105 a sliding sash and a swinging sash mounted in the window frame, of means operated by the sliding sash during its closing movement to impart a constant direct pull on the storm sash toward a fixed point on the window frame to close the storm sash.

3. The combination with a window frame, 115 a sliding sash and a swinging sash mounted in the window frame, of means operated by the sliding sash during its opening and closing movements to impart, respectively, a constant direct push on the storm sash away from a fixed point on the window frame to open the same, and a constant direct pull on the storm sash toward a fixed point on the window frame to close the storm sash.

4. The combination with a window frame, 125 a sliding sash and a swinging sash mounted in the window frame, of an operating bar attached to said sashes, and a fulcrum on the window frame for the operating bar and arranged to cause the operating bar to impart a constant direct push on the storm

sash away from the window frame to open the same during the opening movement of the window sash.

5. The combination with a window frame, 5 a sliding sash and a swinging sash mounted in the window frame, of an operating bar attached to said sashes, and a fulcrum on the window frame for the operating bar and arranged to cause the operating bar to 10 impart a constant direct pull on the storm sash toward the window frame to close the same during the closing movement of the window sash.

6. The combination with a window frame, 15 a sliding sash and a swinging sash mounted in the window frame, of an operating bar attached to said sashes, and a fulcrum on the window frame for the operating bar and arranged to cause the operating bar to 20 impart a constant direct push on the storm sash away from the window frame to open the same during the opening movement of the window sash and to impart a constant direct pull on the storm sash toward the 25 window frame to close the same during the closing movement of the window sash.

7. The structure defined in claim 6 in which the operating bar is in the form of a spring bar.

30 8. The structure defined in claim 6 in which the fulcrum is arranged to place the operating bar under tension when the window sash is closed to hold the storm sash closed.

35 9. The structure defined in claim 6 in which the operating bar is primarily substantially straight and in the form of a spring bar.

40 10. The structure defined in claim 6 in which the operating bar is detachably attached to the window sash.

11. The structure defined in claim 6 in which the operating bar is pivotally attached to the storm sash and detachably attached to the window sash. 45

12. The combination with a window frame, a sliding sash and a swinging sash mounted in the window frame, of an operating bar attached to said sashes, and opposing fulcrums on the window frame for the 50 operating bar and arranged to cause the operating bar to impart a constant direct push on the storm sash away from the window frame to open the same during the opening movement of the window sash. 55

13. The combination with a window frame, a sliding sash and a swinging sash mounted in the window frame, of an operating bar attached to said sashes, and opposing fulcrums on the window frame for 60 the operating bar and arranged to cause the operating bar to impart a constant direct pull on the storm sash toward the window frame to close the same during the closing movement of the window sash. 65

14. The combination with a window frame, a sliding sash and a swinging sash mounted in the window frame, of an operating bar attached to said sashes, and opposing fulcrums on the window frame for 70 the operating bar and arranged to cause the operating bar to impart a constant direct push on the storm sash away from the window frame to open the same during the opening movement of the window sash and to impart a constant direct pull on the storm sash toward the window frame to close the same during the closing movement of the window sash. 75

In testimony whereof I affix my signature.

CHARLES W. KNIGHT.
